A. D. RAY.
OIL HOLE CLOSURE.
APPLICATION FILED SEPT. 12, 1919.

Patented Apr. 12, 1921.

FIG. 6

Inventor

Albert D. Ray

W. Dunstan, his Attorney

UNITED STATES PATENT OFFICE.

ALBERT D. RAY, OF CLEVELAND, OHIO.

OIL-HOLE CLOSURE.

1,374,886.

Specification of Letters Patent. Patented Apr. 12, 1921.

Application filed September 12, 1919. Serial No. 323,366.

To all whom it may concern:

Be it known that I, ALBERT D. RAY, a citizen of the United States, residing at Cleveland, in the county of Cuyahoga and State of Ohio, have invented certain new and useful Improvements in Oil-Hole Closures, of which the following is a specification.

This invention relates to oil-hole closures, and has for its main object to provide a closure for oil holes, which consists of few parts and simple inexpensive construction and is adapted to be opened by pressing the spout of an oil can thereagainst, and after supplying oil will close automatically upon removing the oil can.

In order that the invention may be clearly understood, the same will be hereinafter fully described as illustrated in the accompanying drawings, and the novel features thereof will be distinctly pointed out in the appended claims.

Similar characters of reference are used to designate corresponding parts in the several views of the drawings.

Figure 1 of the drawings is a side elevation of an oil hole closure constructed in accordance with my invention.

Fig. 2 is a similar view showing the opposite side,

Fig. 3 is a plan view of Fig. 1,

Fig. 4 is a sectional view, on an enlarged scale, taken on line 4-4 of Fig. 1,

Fig. 5 a bottom view of the oscillating cover, and

Fig. 6 illustrates the opening of the cover, and the action of the coiled spring thereon for closing the same.

Referring to the drawings, 1 represents a semi-spherical head formed integrally with a threaded shank 2, which is adapted to be screwed into an oil opening by the application of a wrench to a nut shaped flange 3 at the base of said head. A central opening 4 is provided in said head and shank for admitting oil to the opening into which the shank is screwed. The opening 4 is enlarged at 5 to serve as an oil reservoir. For closing the opening 4, a cover 6 is arranged to oscillate upon the semi-spherical head 1 and across the entrance to the opening 4. Said cover consists of thin sheet material which is bent to conform to the semi-spherical head 1, and one of its sides 7 tapers to an inwardly extending pivot 8 and its other side 9 tapers to an inwardly extending plate

10 and pivot 11. The semi-spherical head 1 is provided at one side with an opening 12 for receiving the pivot 8 and at its opposite side with an opening 13 for receiving the pivot 11. In order to allow clearance for permitting the cover 6 to oscillate, the openings 12 and 13 are enlarged at 15 and 16 respectively. For retaining the cover 6 in its normal closed position and for returning it to said position when released after being opened, a coiled spring 17 is seated in an opening 18 of the flange 3 and is adapted to exert upward pressure upon the pivot plate 10. A boss 19 projects from the pivot plate 10 within the coiled spring 17, and serves to prevent that end of the spring slipping from said pivot plate when the cover 6 is oscillated. To facilitate the pushing over or opening of the cover 6 by means of an oil can spout indicated by 20, and for guiding the same to the entrance of the oil opening 4, the center of each edge of said cover is indented and slightly rolled at 21.

In practice, the oscillating cover 6 is a sliding fit over the semi-spherical head 1 to insure it being dust proof, and on account of its rounding form, it does not allow water to enter the oil opening 4. When the cover 6 is oscillated to either side, the action of the pivot plate 10 compresses the far side of the coiled spring 17, and upon releasing the cover, the compressed side of the spring naturally exerts greater pressure upon that side of the pivot plate and forces the cover to normal closed position.

Having fully described my invention, what I claim is:

1. In an oil hole closure, the combination of a body having an opening therein, a cover, the cover having pivots formed integrally therewith, and the cover being pivoted to the body for oscillating thereupon to close said opening, substantially as described.

2. In an oil-hole closure, the combination of a spherical body having an opening therein, a cover, the cover having pivots, the body being provided with openings for receiving said pivots, and means acting against one of said pivots tending to retain the cover in its closed position over the entrance of said opening in the body, substantially as described.

3. In an oil-hole closure, the combination of a spherical body having an opening there-

in, a cover, the cover conforming to the spherical body for sliding thereover, pivots projecting inwardly from the cover, the body being provided with openings for receiving said pivots, and a spring acting against one of said pivots tending to force the cover upwardly for retaining it in closed position over the opening in the body, substantially as described.

- 10 4. In an oil-hole closure, the combination of a spherical body having an opening therein, a cover, the cover consisting of sheet material and conforming to the spherical body for sliding thereover, one side of the cover terminating in an inwardly extending pivot, the other side of the cover terminating in an inwardly extending plate and pivot, said body being provided with openings for receiving the first mentioned pivot and said 20 plate and pivot, and a coiled spring exerting pressure against said plate whereby the cover is retained in closed position over the

opening in the body, substantially as described.

5. In an oil-hole closure, the combination 25 of a spherical body having an opening therein, a cover, the cover consisting of sheet material and conforming to the spherical body for sliding thereover, one side of the cover terminating in an inwardly extending pivot, the other side of the cover terminating 30 in an inwardly extending plate and pivot, said body being provided with openings for receiving the first mentioned pivot and said plate and pivot, a coiled spring exerting pressure against said plate whereby the cover is retained in closed position over the opening in the body, and a boss projecting from said plate within the coiled spring 35 for preventing slipping of that end of the spring when the cover is oscillated, substantially as described.

In testimony whereof I affix my signature.

ALBERT D. RAY.
